ELECTRIC ORGAN

William Hakkarinen, Washington, D. C.

Application December 17, 1947, Serial No. 792,164

10 Claims. (Cl. 84—1.26)

1

My invention relates particularly to electronic systems and more particularly to a circuit arrangement for electric organs.

One of the objects of my invention is to provide a circuit arrangement for an electric organ of great simplicity which may be inexpensively manufactured.

Another object of my invention is to provide an electric circuit arrangement in which the control keyboard may be operated at a safe potential above earth and may be uninsulated and not constitute a hazard to the operator with respect to possible electric shock during operation of the organ.

Another object of my invention is to provide an improved circuit arrangement for generating a wide range of audible frequencies over the musical scale employing a minimum of electric equipment.

A further object of my invention is to provide a circuit arrangement for generating musical notes including an electric circuit in which the dynamic plate-cathode resistance is a function of the cathode-plate current for producing different oscillation frequencies.

A still further object of my invention is to provide an electron tube circuit arrangement for electric organs in which power losses may be introduced into the plate circuit in proportion to changes in dynamic resistance for developing, across a load impedance in the electron tube circuit, conditions which cause the generation of oscillations at different frequencies.

A still further object of my invention is to provide an arrangement of keyboard operated electric organ oscillation circuits controllable over a musical frequency range which may be readily associated with the radio and audio frequency portion of a conventional radio broadcast receiver for utilizing the sound reproducing system of a radio receiver as a reproducer of musical notes under control of the electric organ covered by my invention.

A still further object of my invention is to provide an improved construction of keyboard for electric organ circuits comprising a metallic stamping having intricately related finger-controlled resiliently displaceable key members.

Other and further objects of my invention reside in the improved circuit arrangement for electric organs and keyboard control therefor as set forth more fully in the specification hereinafter following, by reference to the drawings, in which:

Figure 1 schematically illustrates the keyboard

2

controlled oscillator system of my invention for impressing a wide range of frequencies upon an audio frequency amplifier and sound reproducing circuit;

5 Fig. 2 is a plan view of the keyboard controlled assembly for the oscillator system illustrated in Fig. 1 and schematically illustrating the manner of connection thereof to an audio frequency amplifying and sound reproducing system or to

10 a head set for reproduction of the musical notes;

Fig. 3 is a transverse sectional view taken substantially on line 3—3 of Fig. 2 and illustrating on an enlarged scale the construction of the keyboard employed with the organ circuit of my invention; and

15 Fig. 4 schematically illustrates an adaptation of the electric organ circuit of Fig. 1 in which the output signal is impressed between the grid and cathode of an electron tube which is generating radio frequency oscillations. Thus the radio frequency signal is modulated by the signal from the organ and acts as a carrier for the organ signal so that the organ can be played over a nearby radio receiver with no connection between the two required.

20 My invention is directed to an electric organ circuit which is very simple to manufacture and which may be produced on a mass production scale at low cost.

25 The circuit arrangement of my invention eliminates the complicated arrangement of relaxation oscillators and the utilization of various resistor-condenser and inductance-condenser circuit components and the complications of tone

30 frequency generators of the electrostatic and electromagnetic type receiver required in generating tones in electric organs. My invention also eliminates complicated methods of securing audio frequency beat notes from heterodyning high frequency oscillators.

35 In my electric organ the tone frequencies generated are controlled by operating a transformer feed-back vacuum tube oscillator at a very low plate voltage and small plate current, under which conditions the frequency at which oscillations can be sustained varies with the amount of plate current flowing through the electron tube. With fixed capacitor, inductor and resistor values in the oscillator circuit one need only to change the cathode-plate current to cause a change in frequency. It is only necessary, then, to affect the electron tube with means which vary the cathode-plate current, or, what is effectively the equivalent, the dynamic plate re-

sistance of the electron tube to control the generated frequency.

The electric organ of my invention has been developed particularly for use as an attachment to conventional radio broadcast receivers for readily converting the conventional broadcast receiver into an electric organ.

The output of the electric organ circuit of my invention is applied to the radio frequency input or to the audio frequency amplifier and sound reproducing system of the conventional radio broadcast receiver, for reproducing, through the loud speaker of the radio broadcast receiver, the range of musical notes controlled by the electric organ keyboard. It is realized that the electric organ of my invention may be produced as a complete instrument, in itself, embodying an audio frequency amplifier and sound reproducing system. However, from the description herein-after following it will be understood that the electric organ assembly may be a compact unit readily adaptable as an auxiliary device to conventional radio broadcast receivers already available in the home for obtaining much added enjoyment from a conventional radio receiver.

Referring to the drawings in detail, reference character 1 designates a combined rectifier and oscillator tube which, for the purposes of explaining my invention, may be designated as the 117N7 type. The tube includes heater 2 cathode 3 for the oscillator, control grid 4 for the oscillator, screen grid 5 and plate 6. The rectifier portion of the tube includes the rectifier cathode 7 and the rectifier or diode plate 8. The tube circuit is connected to an alternating current system forming a supply line without the interposition of a power transformer to isolate the power line from the direct current voltages required. The power line connection for the circuit is represented at 9 extending through control switch 10 to the heater 2. The direct current voltage required in the tone generating circuits is secured by rectifying the alternating current from the power supply circuit 9 in the diode portion of the tube 1. The isolation of the power line from the direct current voltages required is accomplished by the circuit arrangement including resistors 11 and 12 and 14 connected between the rectifier cathode 7 and one side of the power supply 9 at 9a. Because of the small power and voltage requirements of the tone generator these resistances may be sufficiently large to limit the alternating current which can flow between the oscillator ground and either side of the power line 9 to a value which is non-dangerous to an operator touching the metallic keyboard which is used in the system of my invention.

A non-insulated keyboard is employed with the oscillator system of my invention so it makes no difference whether the operator contacts the keyboard or not. This results from the circuit arrangement by which the oscillator ground is connected to either side of the line supply voltage 9 through resistors 11 and 14 respectively. The frequency generated is varied by limiting the cathode to plate current, that is, the current flow from cathode 3 to plate 6 by the self-biasing action of the amount of resistance from resistor 15 which is included in the circuit between cathode 3, adjustable resistor 16 including adjustable tap 17, and connections through any one of the keys represented at 18, 19, 20, 21 and 22 connected through adjustable taps 18a, 19a, 20a, 21a and 22a on resistor 15, the circuit being com-

pleted through the oscillator ground and through resistor 12 to tap 26. The inductive winding 23 is magnetically coupled with inductive winding 24 through magnetic core 25. Magnetic winding 24 connects between plate electrode 6 and the tap 26 between resistors 11 and 12 in the resistive circuit leading to the power supply line 9 in the path included in the rectifier portion of tube 1. Thus, a regenerative coupling is provided between the control grid circuit of tube 1 and the plate circuit of tube 1 for the generation of oscillations therein. A by-pass condenser 27 connects between the ends of inductive windings 23 and 24 immediately adjacent the control grid 4 and plate 6. The resistive circuit in the rectifier portion of the tube system has shunt connected condensers disposed in a shunt path with the resistors as shown, that is, condenser 28 is connected in shunt with the series arranged resistors 11, 12 and 14 and condenser 29 is connected in shunt with resistor 12. Condenser 29 floats above either side of line potential so that resistors 11 and 14 can effectively isolate tap 26 or oscillator ground from the line shown at 9. The output of the oscillator system is coupled through condenser 30 with the resistive circuit constituted by resistance 31 across which the output terminals 32 connect through the resistance 32.

The keyboard construction employed for the control of the electric organ circuit is illustrated in Figs. 2 and 3. The oscillator system is assembled, as represented at 34 in Fig. 2, on a base support 35 which also provides mounting means for the sub-base 36 which carries the resistor, represented at 15, corresponding to the resistor 15 in Fig. 1. The resistor 15 is generally of the wire-wound type extending vertically to enable adjustable tap connections to be made with the resistance winding by the several taps which I have represented at 18a, 19a, 20a, 21a, and 22a extending from terminal points 18b, 19b, 20b, 21b and 22b, etc., leading to the keys designated in Fig. 1 as 18, 19, 20, 21 and 22 respectively. A symmetrically arranged set of taps is provided adjacent the opposite side of base 36 leading to other keys of the keyboard system. The keyboard system is represented as comprising a pair of flat resilient metallic plates designated by reference characters 37 and 38. The metallic plates 37 and 38 are spacially related to each other by means of the supporting sub-base 39 and the supporting members 40 and 41 carried thereby. Supporting member 40 provides a support for the resilient plate 38. Resilient plate 38 is divided into a multiplicity of transversely extending tongues which form keys and which may be individually depressed to establish electrical connection with contact members supported beneath the ends of the keys, as represented, for example, in Fig. 3. Similarly, resilient plate 37 is supported on supporting member 41 and the individual keys thereof may be depressed to establish connection with the contacts positioned beneath the plate as represented at 43. The contacts 43 are arranged at spaced intervals along the strip of insulation material 65 mounted on supporting member 66 as shown. Each of the plates 37 and 38 are slotted, as represented at 37a and 38a to provide, in effect, a combined structure in which the laterally extending flexible resilient strips constitute keys of the organ and may be depressed to establish connection with the contacts located below the ends of the strips. Resiliency or flexibility is imparted to the several keys by reason of the punched out or slotted con-

struction represented at 37a and 38a which may be further augmented by the recessed construction represented for example at 37b and 37c. In order to simulate a piano or organ keyboard I may omit certain of the keys in the positions 37d, 37e, etc. Also, I further simulate a conventional keyboard by painting the keys 37 black and keys 38 white. Thus, different values of resistance on the tap resistors 15 may be introduced into the cathode plate circuit. The output of the oscillator system at 32 may be connected through lead 46, represented in Fig. 2, to a plug connector 44, which may be inserted into the audio frequency input of the conventional radio broadcast receiver so that the amplifier and sound reproducing system of the conventional radio broadcast receiver operates to reproduce the musical notes secured by changes in the cathode resistor 15. In the arrangement shown I have successfully covered the range of musical notes G₃ through F₆ but I desire that it be understood that various ranges may be readily covered. Where it is desired to reproduce merely the musical notes developed by the oscillator system, without amplification through the broadcast receiver, the output circuit 32 is connected to the head telephone receivers 45, as represented in Fig. 2. The power line cord is 47 and the male connector 48.

The cathode plate current flow is interrupted by the keyboard action to prevent any time delay from the closing of a keyboard switch and the generation of a frequency such as would occur if the keyboard switch only acted in the grid to cathode circuit.

The amplifier circuit is made to feed back to its own input circuit a voltage of the proper phase and amplitude for generating oscillations. The necessary conditions are that the voltage fed back from the output circuit is about 180 degrees out of phase with voltage developed across the load impedance in the plate circuit and that the feed-back voltages have sufficient magnitude to develop the output power necessary to produce the input voltage. In this circuit the phase difference required is mostly developed by the feed-back transformer when properly connected. The frequency at which the oscillations occur in this low power oscillator circuit, in which resonant circuits are not used, is the frequency at which the feed-back voltage is of exactly the proper phase and amplitude to permit the electron tube to supply the requisite input voltage. Therefore, when the plate current is limited to certain various values, the power output developed across the load impedance is varied and as the frequency at which oscillations can occur is a function of the power developed across the load impedance which, in turn, is governed by the cathode to plate current within the tube, the frequency is controlled by the amount of plate current flowing.

Viewed from another angle, the dynamic plate-cathode resistance is in function of the cathode-plate current flowing. Thus, the power losses introduced into the plate circuit vary with the changes in the dynamic resistance, and, as a result of these losses, the power developed across the load impedance varies, which is a condition to permit the oscillator to supply different frequencies. The adjustable multi-tapped resistor 15 is used either as a voltage divider or the equivalent of a bank of variable resistors. With this arrangement the organ can be tuned to exactly the desired frequencies even though the elec-

trical characteristics of the vacuum tube 1 and the transformer 23—25—24 may vary widely.

Referring to Fig. 4 in detail, reference number 49 designates a combined rectifier and amplifier tube similar to electron discharge tube 1 in Fig. 1, except for the heater 50 which is supplied with a different voltage. Another electron discharge tube 51 with heater 52 in series connection with heater 50, has a cathode 53, control grid 54, screen grid 55, and plate 56, and is used to generate a radio frequency signal in conjunction with inductor winding 57 which is regeneratively coupled to inductor 58. Condenser 59 resonates inductor 58 and the tuned circuit is coupled to the control grid 54 by condenser 60. The audio frequency signal is coupled through condenser 39 to resistor 62 which connects to cathode 53 and to resistor 61 joined to the grid 54. Resistor 63 connects tap 26 to inductor 57 and plate by-pass condenser 64 which joins to cathode 53.

The oscillator system connected with tube 51 is designed to produce radiation over a sufficient distance to couple with the circuits of the standard broadcast receiver arranged in the field of the oscillator so that no physical connection between the organ unit and the broadcast receiver is required. Moreover, the constants of the circuit of the oscillator of tube 51 are designed so that modulation may be produced over the entire frequency spectrum determined by the changes in dynamic anode-cathode resistance of tube 49 for thereby reproducing musical frequencies by reception of the radiated signal energy from the organ unit picked up on the radio frequency and intermediate frequency circuits of the standard superheterodyne or other type of receiver leading to the detector and audio frequency amplifier and loud speaker of the standard receiver. Radiation is effected from the inductor 57 and other parts of the circuit connected with oscillator tube 51.

The system of my invention has been found to be very practical in operation and considerably adds to the enjoyment of the use of the conventional radio broadcast receiver when operated from time to time as an electric organ.

I realize that modifications may be made in the circuit arrangement and the manner of applying the generated frequencies to the sound reproducing system, and I desire it to be understood that no limitations upon my invention are intended other than may be imposed by the scope of the appended claims.

What I claim as new and desire to secure by Letters Patent of the United States is as follows:

1. A system for producing electrical oscillations comprising an electron tube including at least a cathode, a control grid, and an anode, an input circuit interconnecting said cathode and control grid, an output circuit interconnecting said anode and cathode, means regeneratively coupling said circuits for the production of oscillations, a resistance connected in common to said input and output circuits, a multiplicity of progressively arranged taps on said resistance terminating in contacts, keys depressible to contacting relation with said contacts and connected in a path common to said input and output circuits for effecting step by step loading of both said input and output circuits and an additional resistance connected in said input circuit and selectively adjustable for variably loading said input circuit.

2. A system for producing electrical oscillations comprising an electron tube including a cath-

ode, a control grid, and an anode, an input circuit interconnecting said cathode and control grid, an output circuit interconnecting said anode and cathode, means regeneratively coupling said circuits for the production of oscillations, a resistance device, a plurality of progressively arranged taps on said resistance device, a multiplicity of depressible keys having coating contacts aligned therewith, a connection extending from said cathode to said keys, connections extending from said coating contacts to said taps, and an additional resistance device connected in circuit with said input circuit and selectively adjustable for variably loading said input circuit.

3. A system for producing electrical oscillations comprising an electron tube including a cathode, a control grid, and an anode, an input circuit interconnecting said cathode and control grid, an output circuit interconnecting said anode and cathode, means regeneratively coupling said circuits for the production of oscillations, a resistance device connected in a path common to said input and output circuits, a multiplicity of progressively arranged taps on said resistance device, contacts connected to each of said taps, selectively depressible keys coating with each of said contacts for introducing into said circuits predetermined increments of power losses for correspondingly changing the frequency of oscillation of said circuits, and an additional resistance device connected in circuit with said input circuit and selectively adjustable for variably loading said input circuit.

4. A system for producing electrical oscillations comprising an electron tube including a cathode, a control grid, and an anode, an input circuit interconnecting said cathode and control grid, an output circuit interconnecting said anode and cathode, means regeneratively coupling said circuits for the production of oscillations, means for selectively producing increment by increment changes in the dynamic plate-cathode resistance of said circuits for producing corresponding changes in the cathode-anode current flow in said circuits, and separate means connected in circuit with said input circuit and selectively adjustable for variably loading said input circuit.

5. A system for producing electrical oscillations comprising an electron tube including a cathode, a control grid, and an anode, a separate cathode and anode, an input circuit interconnecting said first mentioned cathode and said control grid, an output circuit interconnecting said first mentioned cathode and anode, means regeneratively coupling said circuits for the production of oscillations, a source of alternating current, a heater for each of said cathodes energized from said source of alternating current, circuit connections for said second mentioned separate cathode and anode for rectifying said alternating current and applying the rectified current to said circuits, a resistive load having a series of progressively arranged taps thereon, contacts connected with said taps, keys selectively depressible into contacting relation with said contacts, a circuit extending through said resistive load and through said keys in a path common to said input and output circuits, and a separate resistive load connected in circuit with said input circuit and selectively adjustable for variably loading said input circuit.

6. A system for producing electrical oscillations comprising an electron tube including a cathode, a control grid, and an anode, a separate cathode and anode, an input circuit intercon-

necting said first mentioned cathode and said control grid, an output circuit interconnecting said first mentioned cathode and anode, means regeneratively coupling said circuits for the production of oscillations, a source of alternating current, a heater for each of said cathodes energized from said source of alternating current and applying the rectified current to said circuits, an impedance load having a series of progressively arranged taps thereon, contacts connected with said taps, keys selectively depressible into contacting relation with said contacts, a circuit extending through said impedance load and through said keys in a path common to said input and output circuits, and a separate impedance load connected in circuit with said input circuit and selectively adjustable for variably loading said input circuit.

7. A system for producing electrical oscillations comprising an electron tube including a cathode, a control grid, and an anode, an input circuit interconnecting said cathode and control grid, an output circuit interconnecting said anode and cathode, means regeneratively coupling said circuits for the production of oscillations, means for producing step by step changes in the dynamic anode-cathode effective resistance for producing corresponding changes in cathode-anode current flow, a coating electron tube circuit comprising an oscillator, a resistor element having a multiplicity of spaced progressively arranged taps thereon, a multiplicity of selectively controllable playing keys individual to said taps, said resistor element and said keys being connected in circuit between the control grid and cathode of said first mentioned tube, and means controlled by changes in current flow in said first mentioned circuits for determining the frequency of operation of said oscillator over the range of frequencies resulting from changes in the dynamic anode-cathode resistance of said first mentioned circuits.

8. A system for producing musical tones, an electron tube including a cathode, a control grid, an anode, an input circuit interconnecting said cathode and control grid, an output circuit interconnecting said anode and cathode, means regeneratively coupling said circuits for the production of oscillations, a resistive device connected in common with both said input and output circuits, a multiplicity of progressively arranged taps on said resistive device, contacts connected to each of said taps, separate resistive means for variably loading said input circuit, and selectively depressible keys coating with each of said contacts for supplying said input and output circuits with predetermined increments of direct current power, said increments of direct current power producing corresponding increments of alternating current power in the output circuit, and said increments of alternating current power in said output circuit controlling the frequency of oscillation of said circuits.

9. A system for producing musical tones, an electron tube including a cathode, a control grid, an anode, an input circuit interconnecting said cathode and control grid, an output circuit interconnecting said anode and cathode, an audio frequency transformer system including a pair of electromagnetically coupled windings with one of said windings in said input circuit and the other of said windings in said output circuit for regeneratively coupling said circuits for the production of audio frequency oscillations, a resistance device common to said input and output circuits, a multiplicity of progressively arranged

taps on said resistive device, contacts connected to each of said taps, a separate adjustable resistance device individual to said input circuit, selectively depressible keys coacting with each of said contacts for supplying said input and output circuits with predetermined increments of direct current power, said increments of direct current power producing corresponding increments of alternating current power in the output circuit, said increments of alternating current power in said output circuit controlling the frequency of oscillation generated by said circuits.

10. An oscillator for developing non-linear voltage waves of complex form comprising a thermionic tube including at least a cathode, a control electrode and an anode, a circuit path connected between said control electrode and said cathode, said path including an adjustable resistor, a multiplicity of keys, a multiplicity of contacts coacting with said keys, a resistor element in said circuit path having progressively arranged spaced taps thereon, connections between said taps and said contacts, the end of said resistor element which connects with said circuit path being connected to a point of predetermined potential, a transformer winding included in said circuit path and connected to said point of predetermined potential and to said control electrode of said thermionic tube, a capacitor directly connected between said control electrode and said anode of said thermionic tube, a trans-

former winding coupled in feedback relation to said first mentioned transformer winding and connected intermediate the said anode and a point of positive potential, output terminal means, a circuit including a pair of resistors, a condenser connected to said anode and to a common connection to said pair of resistors, the first of said resistors being connected between said last named condenser and said point of predetermined potential, and the second of said pair of resistors being connected in series with said output terminal means and said point of predetermined potential.
